CONTROL DEVICE FOR CHANGE-SPEED GEARS

Jean Albert Gregoire, Paris, France

Application October 25, 1948, Serial No. 56,297
In France October 29, 1947

4 Claims. (Cl. 74—473)

1

The present invention relates to control devices for change speed gears, such as those that are ordinarily used in road or similar vehicles.

It relates more specifically to control devices incorporating a lever that can be shifted into different positions according to the different speeds, no matter whether the said lever is located upon the dashboard, next to the driver or under the wheel.

This invention applies more particularly to change speed gear devices of the type having at least four speeds (one of which is over multiplied for instance) and a reversing gear.

In control devices of this type which are known so far and which generally include, in the gearbox itself, three sliding gears, it was necessary up to now to provide for five different positions of the speed gear lever. The trouble about this device was that on the one hand it was rather complicated to have to operate a device rather different from the one that is found on most present day vehicles which only have three speeds and a reverse.

The present invention has for its object to do away with these inconveniences.

To this purpose, it consists essentially in providing with a speed gear having four speeds and a reversing gear, only four positions of the gear lever, the same position being used for two separate speeds, the second and the fourth or over-multiplied one for example, but requiring when it is desired to go into one of these particular speeds, the additional operation of an auxiliary part which is either a small lever or a knob, etc. This device then shows the following advantages: to go into first, second or third or reverse, the operation is exactly the same as with an ordinary car. When it is desired to go from third into fourth however, the lever must be pulled back from the third into the second speed position while acting upon the auxiliary part. When afterwards it is desired to return from the fourth into the third, the operation is done without acting on the auxiliary part.

The result in question can be obtained through the operation of a system made up of two antagonistic springs, one of which can be operated directly, when required, by the auxiliary part, in such a manner that the selective action upon the sliding gear is no longer effected upon the sliding gear corresponding to the second speed, but on the sliding gear corresponding to the fourth speed.

Other purposes and characteristic features of the present invention will appear in the course

2

of the following description referring to the accompanying drawings illustrating diagrammatically, by way of non limitative examples, a form of execution of the invention as applied to a motor car speed gear control device operated by a lever provided under the steering wheel. In said drawings:

Fig. 1 shows in the usual diagrammatical manner the different positions that can be assumed by a speed gear control lever in a system executed in conformity with the present invention.

Fig. 2 is a diagrammatic view of the speed gear control device in the position which permits the engagement of the second and third speeds.

Fig. 3 is a similar view in a position corresponding to first speed or reverse.

Fig. 4 shows again the same view but in a position corresponding to the fourth or over multiplied speed.

Fig. 5 is a sectional view on a larger scale along the line 5—5 in Fig. 2.

Fig. 6 is a detail sectional view also on a larger scale along the line 6—6 in Fig. 3.

In Fig. 1, the positions of the lever when it is in neutral position, in reverse and in the first three speeds 1—2—3 have been shown diagrammatically at M, AR, I, II and III. The position of the lever for the fourth or over multiplied speed is the same as for the second speed, as shown at S'. The device operates as follows: starting from the neutral point M, it is possible to enter reverse or else separately or successively, in the known manner, each of the positions I, II and III which correspond to first, second and third speed.

When it is desired to go into fourth or over multiplied position with the lever in the position III it is necessary to act on the auxiliary part and to pull back the said lever into the position II-S.

Under the action of this auxiliary control part, it is not the second speed sliding gear which has been operated but the fourth speed sliding gear. When it is desired to return into third, it is possible to move directly over from the position S to the position III, without acting again on the auxiliary control part. Similarly when shifting from third to second, it is necessary to move the lever from III to II again without touching the auxiliary control part. Thus the driver has within reach operating means that are quite similar to those provided in ordinary three speed motor cars. Besides, the control device is just as little cumbersome and easy to

fit on as speed control devices of three speed systems and, consequently, is much less cumbersome and complicated than the four speed control devices that are now in use.

Referring to Figs. 2 and 3, the top left hand side part in the figure shows diagrammatically the parts in the gear box itself. The latter includes three sliding gears that are operated with a known procedure by three sliders 1, 2 and 3. Slider 1 corresponds to the first sliding gear operating the first and reverse speed; slider 2 operates the second and third speeds; slider 3 operates the fourth or over multiplied speed. The operating control member for these sliders has been diagrammatically shown in Fig. 4 and also on a larger scale in Fig. 5. This member can be worked, as will be explained later on, into the three positions of preselection that are shown in Figs. 2, 3 and 4 and this preselecting movement brings it either opposite the slider 2 or opposite the slider 1 or opposite the slider 3. In each one of these positions, the same member can also assume a rotary or engaging movement in a manner that will also be disclosed hereinafter. This movement of rotation causes the corresponding slider to move towards the right or the left and bring either speed into gear.

In Fig. 5, the said control part 4 is seen when supposed to be in front of slider 1. It consists of a lever 4 to which a movement of rotation is impressed round a shaft 5 in the way described hereinbelow. Its round end 6 engages a notch 7 on the slider and it will easily be understood, consequently that this rotation causes the slider to move either to the right or to the left as shown in dotted lines for engaging into reverse or into first speed. A certain amount of play is provided between the lever end 6 and the notch 7, this play corresponding to the maximum float of the engine unit. The preselection movement of the control member 4 that is to say its sliding movement is obtained through a traction cable 8 (which is operated as will be explained hereinafter) which acts upon it in register with a spring 9. Its movement of rotation is executed by means of a link 10 (see more particularly Fig. 5) which forms one and the same piece with the tube 11, along which the hub of lever 11 slides. A bolt pin 12, rigid with the lever 4 and which slides in a longitudinal groove of the tube 11, causes the control lever 4 to rotate together with the link 10 without hindering its sliding movement.

It will now be explained how the motion of the control part 4 itself is operated by the speed control lever 13 located under the steering wheel, an auxiliary lever 14 being provided for the control of the fourth or over multiplied speed.

The lever 13 is pivotally secured at 15 to a sheath 16 carried by an outwardly spherical sleeve 17 mounted with a ball and socket joint in a support 18 which is carried by the steering column 19. Said sheath 16 is mounted in such a manner as to be capable of rotating inside the rotula support 17 without moving axially with reference to the latter.

Inside this sheath, a tube 20 can rotate and slide, the opposite end of which tube is rigid with a tube 21 of a slightly larger diameter, which tube can also rotate and slide inside an outwardly spherical sleeve 22 which is mounted as a rotula inside a support 23 carried by the steering gear 24. The supports 18 and 24 are arranged in such a manner that the tube 20 assumes a position which is substantially parallel or slightly inclined in relation to a steering column 19 which carries the wheel 25. Inside the tube 20 there

is arranged a cage 26 provided with a longitudinal slot 27 registering with a similar slot in the tube 20 in order to allow the passage through it of the pivot 15 around which the lever 13 rotates in relation to the sheath 16, said slots being designed so as to allow the sliding movements of the tube 20 and the cage 26 in relation to the sheath 16. To the cage is hooked the end 28 of the traction cable 8 leading to the speed box; as a matter of fact, this cable is not in one piece but comprises a screw and nut junction device for adjusting the length of the cable and thereby the position of the part 4 in relation to the lever 13. A spring 30 is inserted between the cage 26 and an abutment 31 provided on the tube 20. This spring which is strongly compressed is, according to the invention, much stronger than the spring 9 of the speed box, for reasons that are disclosed hereinbelow.

Besides, a lever 32 connected with the lever 10 through the agency of a link 33 is used for transmitting the rotary movement of the tube 20 to the control lever 4. This lever 32 is for this purpose mounted by means of grooves, that are not visible on the drawing, or of any suitable device, in order to be capable of sliding along the tube 20 while remaining constrained to rotate in unison with said tube. To this arrangement, there is incorporated a stud operated device which will be described later on with reference to Fig. 6.

The rotating and sliding movement of the tube 20 is operated through the lever 13 in the following manner: said tube 20 is rigid with a part 34 at its upper part (on the right of Fig. 2) which is shaped as shown and terminates in a round head 35 sliding inside a sleeve 36 carried by the lever 13. When the lever is tilted backwards in the plane of the figure, it is obvious that such a movement of the lever, as it rotates round the pivot 15, causes through action on part 34, the whole of the tube 20 to slide. Besides, when the said lever is made to rotate perpendicularly to the plane of the figure, the lever causes the tube 20 to rotate through the agency of the pivot 15.

The lever 14 is pivoted to the part 34 round a spindle 37. The other end of this lever 14 has two shoulders 38 and 39 shaped as shown. The shoulder 39 which, in the position illustrated in Fig. 2, bears against the tube 20, is used for limiting the movement of the lever 24 towards the left hand side of the figure. The shoulder 38 bears against the upper end of the cage 26. When the lever 14 is hand shifted outwardly in order to move it nearer to the lever 13, such a movement causes through the agency of the shoulder 38, the cage to be pushed inwardly against the spring 30, thereby giving the effects which are indicated below.

The device just described operates as follows, examining first the speed engaging movement. The apparatus being for example in the position shown in Fig. 2 and the lever 13 in the position C, the rotation of this lever in a plane perpendicular to the figure brings about, as already mentioned, a rotation of the tube 20 and consequently of the lever 32, whereby through the link 33 and the lever 10, the control part 4 is actuated which shifts the slider 2 to the right or to the left that is to say into a position that puts into gear either the second or the third speed, according as to whether the lever 13 is moved to the right or to the left of the plane of the drawing. This putting into gear is performed in the same way of course when the control part 4 is in front of the first or of the reverse speed (Fig. 3) or in front of the over multiplied speed (Fig. 4).

Examining now the sliding or preselection movement of the control part 4, it is apparent that so long as the lever 14 is not operated, the spring 30 being much stronger than the spring 9, the whole system including the tube 20 and the cage 26 forms a rigid block. The result is that the sliding of the tube 20, which is caused by the tilting movement of the lever 13, as has been explained hereinabove, is entirely transmitted to the control part 4 through the cable 8. This allows moving from the position shown in Fig. 2 to the position in Fig. 3 and reversely by simply tilting the lever 13 in the plane of the figure, such a tilting movement causing the control part 4 to move from the position in Fig. 2 (preselection of the slider 2) to the position in Fig. 3 (preselection of the slider 1) and reversely.

If, on the contrary, the lever 13 being in the position shown in Fig. 2, that is to say the position where the tube 20 is in its innermost sliding position, the lever 14 is pulled outwardly in the plane of the figure, the shoulder 38 of said lever bears on the cage 26 and compresses the spring 30. The spring 9, which is no longer counterbalanced by the spring 30, urges the control part 4 forwards and brings it into register with the slider 3 (Fig. 4). The transversal rocking of lever 13, acting upon the control part 4, will then bring about the engagement into fourth or overmultiplied speed. At that moment, the auxiliary lever 14 can be let go, which lever is urged back into its original position by a small spring which is not illustrated, the fourth or over-multiplied speed remains in gear.

To return to any of the other speeds, it is only necessary first to pull back the main lever 13 to the neutral inoperative position M (Fig. 1), then to engage the desired speed in the manner already disclosed. As soon as the part 4 is back in neutral position (as shown in solid lines in Fig. 5), the spring 30 acts on the cable 8 and pulls the part 4 back into the position shown in the Fig. 2 corresponding to preselection of the second and third speeds.

A few additional arrangements will now be described.

When in reverse or first speed (Fig. 3), to avoid passage by mistake into over multiplied speed, an abutment 49 is provided on the lever 13 and prevents the operation of the auxiliary lever 14.

On the other hand, a stud 41 carried by the tube 21 in front of the lever 32 (see more particularly Fig. 6) moves in front of a plate 42 which is shaped as shown and provided with a notch adapted to register with said stud when the lever 32 is in its neutral position illustrated at M. This stud bearing upon the plate 42, as can be seen in Figs. 3 and 6, prevents the lever 13 from coming under the action of the spring 9, into the position II-III in Figure 2, as long as the lever 32 is in one of its laterally shifted positions.

What I claim is:

1. A change speed gear including a change speed lever adapted to assume two operative positions to either side of a neutral position in each of two operative planes corresponding respectively to reverse and first forward on one hand and to second and third on the other, the position of modified third being the same as for second forward, two couples of speed controlling shift rods corresponding respectively to the couples of positions in each of said planes, the shift rods of the couple corresponding to the two first positions lying to the front of the couple providing the two following positions, an intermediary member

adapted to be shifted longitudinally and then transversely for engaging selectively either of said shift rods and to shift same into an operative position for obtaining the corresponding speed, 5 a transmission including a stout spring and a sliding part urged rearwardly thereby, said transmission operatively connecting the control lever with the intermediary member for producing said longitudinal and transversal movements of said intermediary member, a further shift rod located beyond the above mentioned couples of shift rods and adapted to be operatively engaged by the intermediary member and to be shifted thereby into a position providing modified third through a further longitudinal movement thereof followed by a transversal movement, a weaker spring urging said intermediary member into the direction corresponding to engagement with the further shift rod, an auxiliary control member associated with the control lever and adapted to urge the sliding part forwardly against the action of the stout spring for urging the part of the transmission lying beyond said sliding part and therewith the intermediary member forward by a distance equal to that separating the second couple of shift rods from the further shift rod and means urging said auxiliary control member back into its inoperative position.

2. A change speed gear including a change speed lever adapted to assume two operative positions to either side of a natural position in each of two operative planes corresponding respectively to reverse and first forward on one hand and to second and third on the other, the position of modified third being the same as for second forward, two couples of speed controlling shift rods corresponding respectively to the couples of positions in each of said planes, the shift rods of the couple corresponding to the two first positions lying to the front of the couple providing the two following positions, an intermediary member adapted to be shifted longitudinally and then transversely for engaging selectively either of said shift rods of either couple and to shift same into an operative position for obtaining the corresponding speed, a transmission including a stout spring and a sliding part urged rearwardly thereby, said transmission operatively connecting the control lever with the intermediary member for producing said longitudinal and transversal movements of said intermediary member, a further shift rod located beyond the above mentioned couples of shift rods and adapted to be operatively engaged by the intermediary member and to be shifted thereby into a position providing modified third through a further longitudinal movement thereof followed by a transversal movement, a weaker spring urging said intermediary member into the direction corresponding to engagement with the further shift rod, an auxiliary control member associated with the control lever and adapted to urge the sliding part forwardly against the action of the stout spring for urging the part of the transmission lying beyond said sliding part and therewith the intermediary member forward by a distance equal to that separating the second couple of shift rods from the further shift rod and means urging said auxiliary control member back into its inoperative position and an abutment on the control lever preventing operation of the auxiliary control member when the lever is in the position corresponding to reverse and first forward.

3. A change speed gear including a change

speed lever adapted to assume two operative positions to either side of a neutral position in each of two operative planes corresponding respectively to reverse and first forward on one hand and to second and third on the other, the position of modified third being the same as for second forward, two couples of speed controlling shift rods corresponding respectively to the couples of positions in each of said planes, the shift rods of the couple corresponding to the two first positions lying to the front of the couple providing the two following positions, an intermediary member adapted to be shifted longitudinally and then transversely for engaging selectively either of said shift rods of either couple and to shift same into an operative position for obtaining the corresponding speed, a transmission including a stout spring and a sliding part urged rearwardly thereby, said transmission operatively connecting the control lever with the intermediary member for producing said longitudinal and transversal movements of said intermediary member, a further shift rod located beyond the above mentioned couples of shift rods and adapted to be operatively engaged by the intermediary member and to be shifted thereby into a position providing modified third through a further longitudinal movement thereof followed by a transversal movement, a weaker spring urging said intermediary member into the direction corresponding to engagement with the further shift rod, an auxiliary control member associated with the control lever and adapted to urge the sliding part forwardly against the action of the stout spring for urging the part of the transmission lying beyond said sliding part and therewith the intermediary member forward by a distance equal to that separating the second couple of shift rods from the further shift rod and means urging said auxiliary control member back into its inoperative position and a stationary abutment locking the weaker spring against reaction on the trans-

mission when the auxiliary control member is in one of its speed controlling positions.

4. A change speed gear comprising, in combination: a change speed lever movable to a neutral position and to an operative position on each side of the neutral position about a substantially vertical axis; said operative positions corresponding to reverse and forward gears, and to second and third forward gears respectively; a second control lever pivoted upon the first named lever and movable in vertical planes at each operative position of the first lever; a plurality of gear shifting members; means controlling said members by movements of said lever; each of said members being movable in two opposite directions; one thereof controlling gears for first forward and for reverse gears; a second member controlling gears for second and third speed gears; and a third controlling a modified third forward gear; a connector sliding coaxially with said vertical axis actuated by the second lever to control said modified third gear shifting member when the first lever is in position for control of the second speed forward gear.
